tion of the lines of folding of the folded portions to facilitate the second folding.

3. A match packet comprising a sheet of flexible material folded in a plurality of directions with the lines of folding intersecting, said material being recessed at the folding intersection, a plurality of match supporting means having groups of matches supported therein, said means being arranged between opposed folded portions of the flexible material, one portion of the flexible material extending continuously across the match supporting means to provide a continuous advertising surface.

4. A match packet comprising a sheet of flexible material folded in a plurality of directions with the lines of folding intersecting, and a plurality of match supporting means having groups of matches supported therein, said means being arranged between opposed folded portions of the flexible material, one portion of the flexible material extending continuously across the several match supporting means and being cut out to form projecting advertising features.

5. A match packet comprising a cover bent into substantially U-shape, a partition member of corrugated form, sheet material secured on opposite sides of the corrugated partition member, the sheet material and corrugated partition member forming compartments to receive matches, the sheet material on one side of the partition including a safety flap extending about the edge of the partition member in closing relation over the inner ends of the compartment about the head portions of the matches, and means for securing the partition and sheet material as a unit to the walls of the cover.

6. A match packet comprising a cover of flexible material, said cover having a folded portion defining a flap and forming a plurality of match supporting sections, said cover being folded along a line transversely of the first line of folding to provide a book-like form, said flexible material being recessed at the area of intersection of the lines of folding to facilitate the second folding operation, said flap extending continuously across, and forming parts of, the match supporting sections and being cut out to provide projecting advertising surface, said sections being provided with compartments, matches disposed in the compartments and projecting therefrom, each match including a length of strip material provided with an intermediate shank portion with ignitable head at one end and a substantially flat enlarged handle portion at the other end forming an advertising surface arranged in contiguous relation with adjacent flat handles of adjacent matches to form a substantially continuous series of advertising surfaces, each compartment having igniting friction material on its inner wall surfaces whereby each match head will frictionally contact with the friction material upon withdrawal of a match from a compartment.

7. A match packet comprising a U-shaped cover, a partition in the cover dividing the packet into two sections for holding matches, said partition extending from the bight of the U-shaped cover outwardly beyond the outer marginal portions of the legs of the U-shaped cover to provide advertising surfaces on opposite sides of the partition beyond the cover edges.

8. A match packet comprising a U-shaped cover, a partition in the cover dividing the packet into two sections, a group of matches disposed in each section on each side of the partition, said partition extending from a location adjacent the

bight of the U-shaped cover beyond opposite side portions of the cover for shielding matches on one side of the partition from matches on the other side of the partition along substantially their entire length.

9. A match packet comprising a single sheet of material arranged in folded form to provide a U-shaped cover, a partition having two laminations providing a wall of double thickness and dividing the packet into two sections for holding matches, said partition extending from the bight of the U-shaped cover outwardly beyond the outer marginal portions of the legs of the U-shaped cover to provide advertising surfaces on opposite sides of the partitions beyond the cover edges, the outer edge of the partition being defined by a fold, a leg portion of the U-shaped cover merging integrally with each lamination of the partition.

10. A match packet comprising a single sheet of material arranged in folded relation to provide a U-shaped cover, said cover including a partition having two laminations providing a wall of double thickness and dividing the packet into two match holding sections, formed into compartments, a group of matches disposed in each section on each side of the partition, each match including a length of flexible material provided with an intermediate shank portion with ignitable head at one end and a substantially flat enlarged handle portion at the other end forming an advertising surface arranged in contiguous relation with adjacent flat handles of adjacent matches to form a substantially continuous series of advertising surfaces, each compartment having igniting friction material on its inner wall surfaces whereby each match head will frictionally contact with the friction material upon withdrawal of a match from a compartment.

11. A match packet comprising a cover of flexible material bent into U-shape, a match holding unit including a series of spaced match containing compartments, means for securing the unit in the cover with compartment ends covered by the bight of the U-shaped construction, one wall of the U-shaped construction extending beyond the unit of compartments, and a series of matches having lines of division along common end portions thereof with such end portions disposed in contacting edge to edge relation, the other match-end portions being disposed in spaced relation corresponding substantially to the spaced relation of the series of compartments, said other match-end portions having ignitable heads fitting into the several compartments and having their opposite said common end portions defining enlarged handles projecting outside the compartments, interior walls of said compartments being provided with friction material whereby the matches are ignited when withdrawn therefrom.

12. A match packet comprising a cover, a partition in the cover dividing the packet into two sections, a series of matches having enlarged handle portions disposed in contacting side by side relation to form a substantially continuous advertising surface, said matches having reduced ignitably headed shank portions, means separately inclosing headed shank portions of the individual matches in each of the sections, said partition extending from adjacent edge portions of the cover for shielding the matches on opposite sides of the partition from one another along substantially their entire length, and means for striking the individual matches as they are withdrawn from the packet.

UNITED STATES PATENT OFFICE

2,130,273

MATCH PACKET

Maurice Greenman, Buffalo, N. Y.

Application January 2, 1937, Serial No. 118,703

12 Claims. (Cl. 206—29)

This invention relates to match packets and it has particular relation to a combined match packet and advertising medium.

The invention relates to an invention disclosed in my previously filed application Serial No. 644,866, filed November 29, 1932.

One object of the invention is to provide an improved cover or holder for matches that is composed of flexible material, such as card board, or the like, and in which the individual matches are enclosed in individual cells or compartments that are provided with striking material to insure igniting of the matches when they are withdrawn from the packet or cover.

Another object of the invention is to provide an improved match packet involving a simple and efficient construction and arrangement designed to minimize the cost of manufacture and to insure safety and certainty in igniting the matches.

Another object of the invention is to provide an improved match packet so formed that the flame of ignition, when one of the matches is being withdrawn, is effectively insulated from the heads of the remaining matches.

Another object of the invention is to provide an improved match packet wherein the user of the matches is directed to observe opposite sides of the packet, or in other words, the matches are so arranged with respect to the cover that, in the natural course of handling the packet and detaching matches therefrom, the several advertising sections will be automatically presented to the user.

In the drawing:

Fig. 1 is a perspective of a match packet in which the invention has been incorporated;

Fig. 2 is a perspective of the match packet shown in Fig. 1 in its open or unfolded position;

Fig. 3 is a vertical section taken substantially along the line III—III of Fig. 2;

Fig. 4 is a fragmentary elevation with portions of structure disassembled to reveal interior arrangement of elements;

Fig. 5 is a perspective of a match packet embodying another form of the invention;

Fig. 6 is a cross section of the packet similar to that shown in Fig. 5, but having a cover and partition formed of a single sheet of material;

Fig. 7 is a cross section taken substantially along the line VII—VII of Fig. 6.

Referring to Figs. 1 to 4, a match packet or cover 10 comprises a sheet of flexible material 11 which is folded or bent along lines 12 to form a bight portion 13, and an intermediate portion of the sheet has a recess 15 formed in the bight portion 13 to facilitate the folding of the sheet along lines 16 transversely of the fold lines 12.

Thus, there are provided a plurality of opposed

advertising surfaces or wall sections 17 and 18. It will be observed by reference to Fig. 2, that the sections 18 are integral and are adapted to provide space for a continuous advertising feature 19 extending across both of them. Also, the fold lines 16 provide for hinge-like action of the sections 17 and 18 which are adapted to be opened and closed in book form and in opposed relation.

A plurality of groups 20 of match receiving cell-like compartments 22 are secured by adhesive, or the like, between the advertising wall sections 17 and 18, and each group is composed of a corrugated partition strip 23 and a backing strip 25 that is disposed along one side of the group of compartments. A safety extension or flap 26 of the backing strip 25 covers the inner ends of the corrugations of the compartments throughout the structure and extend partially up the other side of the group of outer compartments. A plurality of matches 27 cut from sheet material and having enlarged flattened handles 28 are disposed in the compartments 22 with their igniting ends 24 adjacent the bight 13 of the holder. At the outer ends of the compartments 22 suitable match striking material 29 is connected or otherwise applied circumferentially on the inner surfaces of the corrugated strips and backings 25 to insure striking material entirely surrounding each match. The circumferential contour of the striking material in each compartment conforms generally to the circumferential contour of each match head. The several groups 20 of match receiving compartments are supported between the wall sections 17 and 18 by securing means, such as adhesive, or the like.

Proper book-like action of the cover along the lines 16 is insured because the groups 20 are spaced slightly from these lines and their edges are disposed parallel thereto. Thus, each match is completely and separately enclosed along its head end, and since the flaps 26 seal the inner ends of the compartments 22 they prevent flame from escaping to the user's hands or to the other matches when one of the matches is being withdrawn and ignited or struck.

As best shown in Fig. 2, the wall sections 18 terminate adjacent the outer ends of the matches and the edges of these sections are considerably spaced from the edges of the wall sections 17. Thus the handle ends 28 of the matches are exposed against the inner surfaces of the outer wall sections 17 and these ends of the matches are shielded when the packet is viewed from the outside or in its closed position (Fig. 1). These handles 28 also provide a substantially continuous surface in each group 20 upon which suitable advertising matter can be applied.

It will be observed that the tabs or handles 28

are considerably wider than the body portions of the matches and provide convenient handles which can be grasped conveniently between the fingers for removing individual matches from the packet. The contiguous handles of the matches are held in assembled relation in the compartments of the packet to provide a substantially continuous surface across the face of the cover for suitable application of various kinds of advertising matter.

If desired, the matches may be connected at their handles along lines 30 which are adapted to define scoring or weakened portions, or the matches can be independent of each other and substantially abut each other along the lines 30. Accordingly, it is clear that the user in picking up the packet will at least view the advertising matter printed upon one or the other of the outer wall sections 35. Likewise, in opening or unfolding the packet in the hinging action along the lines 16, the advertising matter on the wall sections 18 is inevitably presented to the user. It is to be understood that separate advertising features may be applied to each of the wall sections 18, or a continuous advertising feature 19 can be presented thereon as shown. In this form of advertising folder or cover, another feature which serves to arrest the attention of the user is a portion of the advertising wall sections that are cut out into irregular form, as indicated at 31. This cut-out portion is adapted to take the form of various articles to be advertised, and operates to add to the attractiveness of the packet, as well as to accentuate the advertising value thereof.

In the form of the invention shown in Figs. 5 and 6, a packet 32 is shown in which a sheet of flexible material 33 is bent into substantially U-shape to provide opposed wall sections 35 connected integrally by a bight portion 36. An intermediate or partition wall section 37 is disposed centrally between the sections 35 and its outer marginal portions extend considerably beyond the edges of the wall sections 35 which can be cut out, as indicated at 58, to provide improved and attractive advertising features.

A plurality of groups 38 of match receiving cells or compartments 39 are secured between the advertising wall sections 35 and on opposite sides of the intermediate wall section 37, the latter of which is also adapted to serve as an advertising medium. These groups 38 of compartments are composed of corrugated strips 50, and backing strips 52 that have safety extensions or flaps 53 covering the inner ends of the corrugations or compartments throughout the structure. A plurality of matches 54 having enlarged flattened handles 55 are disposed in the compartments 39 with their igniting ends adjacent the bight 36 of the U-shaped holder. If desirable, the matches may be connected at their handles along lines 56 which are adapted to define scoring or weakened portions, or the matches can be separate or independent of each other and abut each other along these lines 56.

Along the inside portions of the compartments 39 adjacent their outer ends, suitable striking material 57 is connected or otherwise applied to the inner surfaces of the corrugated strips 50 and backings 52 of which the compartments are formed and such striking material completely surrounds each match. The several groups 38 of match receiving compartments are supported and secured between the wall sections 35 on opposite sides of the intermediate wall section 37

by means of a suitable connecting medium, such as adhesive.

As best shown in Fig. 6 the intermediate partition 37 and the side walls 35 can be composed of a continuous sheet of material bent or folded into the form described. In such construction the intermediate partition 37 is of unitary double walls secured by adhesive, or the like.

In using the match packet shown in Fig. 5, one of the matches 54 is grasped by the handle 55 and withdrawn to ignite it by reason of its head frictionally engaging the striking material 57. It will be observed that a group of matches is disposed on each side of the intermediate wall section 37 and that the handles of the matches extend substantially to the outer marginal edge of the intermediate wall section. In this arrangement the advertising matter applied upon one of the wall sections 35 is presented directly to the user. On the other hand, in using the matches from the other side of the intermediate wall 37, the match packet is turned over in the natural course of its use and the advertising matter on the other wall section 35 is then presented to the eyes of the user. In this manner, the entire space of the packet designed for advertising matter is inevitably presented to the eyes of the user, and hence, the advertising value of the packet is greatly enhanced. If desirable, the outer marginal edge of the intermediate wall section 37 can be extended to receive advertising matter, or such matter can be printed thereon behind the match handles to be visible as the matches are exhausted from the compartments.

The cut-out portion 58 can be formed on both of the wall sections 35 and on the intermediate wall section or partition 37, and serve in the same manner as the similar cut-out portion 30 described above with reference to Fig. 2.

It is to be understood that the various contacting surfaces of the elements holding the matches can be secured together by means of cement or other suitable material to such extent as to insure proper maintenance of the elements in assembled relation.

Although only two forms of the invention have been shown and described in detail, it will be apparent to those skilled in the art that the invention is not so limited, but that various changes may be made therein without departing from the spirit of the invention or from the scope of the appended claims.

I claim:

1. A match packet comprising a cover of flexible sheet material, said cover having a line of folding extending across its body, a folded portion of the cover defining a flap disposed in opposed relation to the body of the material and providing therewith a plurality of match holding sections, means for holding individual matches in the sections, the cover material being folded along a line transversely of and intersecting the first line of folding to provide a book-like form.

2. A match packet comprising a cover of flexible sheet material, said material being folded upon itself along a line extending across the body of the sheet material, a plurality of sections of corrugated material disposed in the folded portion of the material to form a plurality of match receiving compartments, said material being folded along a line transversely of and intersecting the first line of folding for closing the cover with the match compartments in opposed relation, the flexible material being recessed at the intersection.

tion of the lines of folding of the folded portions to facilitate the second folding.

3. A match packet comprising a sheet of flexible material folded in a plurality of directions with the lines of folding intersecting, said material being recessed at the folding intersection, a plurality of match supporting means having groups of matches supported therein, said means being arranged between opposed folded portions of the flexible material, one portion of the flexible material extending continuously across the match supporting means to provide a continuous advertising surface.

4. A match packet comprising a sheet of flexible material folded in a plurality of directions with the lines of folding intersecting, and a plurality of match supporting means having groups of matches supported therein, said means being arranged between opposed folded portions of the flexible material, one portion of the flexible material extending continuously across the several match supporting means and being cut out to form projecting advertising features.

5. A match packet comprising a cover bent into substantially U-shape, a partition member of corrugated form, sheet material secured on opposite sides of the corrugated partition member, the sheet material and corrugated partition member forming compartments to receive matches, the sheet material on one side of the partition including a safety flap extending about the edge of the partition member in closing relation over the inner ends of the compartment about the head portions of the matches, and means for securing the partition and sheet material as a unit to the walls of the cover.

6. A match packet comprising a cover of flexible material, said cover having a folded portion defining a flap and forming a plurality of match supporting sections, said cover being folded along a line transversely of the first line of folding to provide a book-like form, said flexible material being recessed at the area of intersection of the lines of folding to facilitate the second folding operation, said flap extending continuously across, and forming parts of, the match supporting sections and being cut out to provide projecting advertising surface, said sections being provided with compartments, matches disposed in the compartments and projecting therefrom, each match including a length of strip material provided with an intermediate shank portion with ignitable head at one end and a substantially flat enlarged handle portion at the other end forming an advertising surface arranged in contiguous relation with adjacent flat handles of adjacent matches to form a substantially continuous series of advertising surfaces, each compartment having igniting friction material on its inner wall surfaces whereby each match head will frictionally contact with the friction material upon withdrawal of a match from a compartment.

7. A match packet comprising a U-shaped cover, a partition in the cover dividing the packet into two sections for holding matches, said partition extending from the bight of the U-shaped cover outwardly beyond the outer marginal portions of the legs of the U-shaped cover to provide advertising surfaces on opposite sides of the partition beyond the cover edges.

8. A match packet comprising a U-shaped cover, a partition in the cover dividing the packet into two sections, a group of matches disposed in each section on each side of the partition, said partition extending from a location adjacent the

bight of the U-shaped cover beyond opposite side portions of the cover for shielding matches on one side of the partition from matches on the other side of the partition along substantially their entire length.

9. A match packet comprising a single sheet of material arranged in folded form to provide a U-shaped cover, a partition having two laminations providing a wall of double thickness and dividing the packet into two sections for holding matches, said partition extending from the bight of the U-shaped cover outwardly beyond the outer marginal portions of the legs of the U-shaped cover to provide advertising surfaces on opposite sides of the partitions beyond the cover edges, the outer edge of the partition being defined by a fold, a leg portion of the U-shaped cover merging integrally with each lamination of the partition.

10. A match packet comprising a single sheet of material arranged in folded relation to provide a U-shaped cover, said cover including a partition having two laminations providing a wall of double thickness and dividing the packet into two match holding sections, formed into compartments, a group of matches disposed in each section on each side of the partition, each match including a length of flexible material provided with an intermediate shank portion with ignitable head at one end and a substantially flat enlarged handle portion at the other end forming an advertising surface arranged in contiguous relation with adjacent flat handles of adjacent matches to form a substantially continuous series of advertising surfaces, each compartment having igniting friction material on its inner wall surfaces whereby each match head will frictionally contact with the friction material upon withdrawal of a match from a compartment.

11. A match packet comprising a cover of flexible material bent into U-shape, a match holding unit including a series of spaced match containing compartments, means for securing the unit in the cover with compartment ends covered by the bight of the U-shaped construction, one wall of the U-shaped construction extending beyond the unit of compartments, and a series of matches having lines of division along common end portions thereof with such end portions disposed in contacting edge to edge relation, the other match-end portions being disposed in spaced relation corresponding substantially to the spaced relation of the series of compartments, said other match-end portions having ignitable heads fitting into the several compartments and having their opposite said common end portions defining enlarged handles projecting outside the compartments, interior walls of said compartments being provided with friction material whereby the matches are ignited when withdrawn therefrom.

12. A match packet comprising a cover, a partition in the cover dividing the packet into two sections, a series of matches having enlarged handle portions disposed in contacting side by side relation to form a substantially continuous advertising surface, said matches having reduced ignitably headed shank portions, means separately inclosing headed shank portions of the individual matches in each of the sections, said partition extending from adjacent edge portions of the cover for shielding the matches on opposite sides of the partition from one another along substantially their entire length, and means for striking the individual matches as they are withdrawn from the packet.
